[57] CLAIM

The ornamental design for an apparatus for slitting elongated flexible tape, as shown.

DESCRIPTION

FIG. 1 is a top left, front perspective view of an apparatus for slitting elongated flexible tape showing my new design;

FIG. 2 is a front elevational view thereof;

FIG. 3 is a top plan view thereof;

FIG. 4 is a left side elevational view thereof;

FIG. 5 is a right side elevational view thereof;

FIG. 6 is a bottom plan view thereof; and

FIG. 7 is a rear elevational view thereof.

FIG. 1

FIG. 2

FIG. 3

FIG. 4

FIG. 5

FIG. 6

FIG. 7
